4 Claims. (Cl. 81—129)

This invention relates to improvements in a slidable side jaw wrench.

One of the objects of this invention is to provide an adjustable wrench with locking means which will positively lock the adjustable jaw member in its adjusted position so that the same will not spread or move with respect to the stationary jaw member during use.

It has been found that one of the principal objections to the prior art adjustable wrenches is that the movable jaw would not stay in its locked position when the wrench was applied to an object in wrenching position but that the movable jaw would spread or move in relation to the stationary jaw thus loosening its grip on the object and necessitating frequent retightening of the locking member on the wrench during a single operation. The foregoing objections have all been eliminated with the present invention.

In accordance with this invention there is provided a locking means which includes a member having a general convex shaped inner surface which extends partially into the slot of the movable jaw member and partially out of the slot and which engages the upper and lower surfaces adjacent the slot along two spaced parallel straight lines. This arrangement provides an effective locking means so that once the locking means is in locked position it will be maintained in locked position irrespective of the force or pressure that might be applied in the use of the wrench on an object.

Other objects will become apparent as this description progresses.

In the drawings:

Figure 1 is a front elevational view of the wrench.

Figure 2 is an end elevational view.

Figure 3 is a rear elevational view showing the movable jaw secured in its closest adjusted position relative to the stationary jaw.

Figure 4 is an enlarged sectional view taken on lines 4—4 of Figure 3.

Figure 5 is an enlarged view showing the locking means, and

Figure 6 is an enlarged sectional view of a portion of the wrench showing a modified form of locking means.

The wrench shown in Figures 1 to 5 inclusive includes an elongated wrench handle generally indicated at 10 which diverges outwardly at the top to form an intermediate section generally indicated at 12 from which upwardly extends the stationary jaw generally indicated at 14. The handle 10, intermediate section 12 and the stationary jaw are integrally forged or cast of malleable iron or the like.

The intermediate section 12, as best shown in Figure 4, is recessed as at 16 to provide a lower shoulder 18 and an upper shoulder 20. The lower shoulder 18 extends transversely of the handle 10 and extends the full length of the intermediate section 12. The upper shoulder 20 is parallel to the lower shoulder 18 and extends below the stationary jaw 14. The adjustable or slid-

2

able jaw member generally indicated at 22 is slidably supported in the recessed intermediate section 16.

The slidable jaw member comprises a lateral extension 24 from which extends an upwardly extending jaw 26, 5 all integrally formed. The lateral extension 24 is adapted to slidably fit within the recessed intermediate section 16 and between the shoulders 18 and 20. The lateral extension 24 is provided with a longitudinal slot 28 which has parallel extending flat upper and lower wall surfaces 29 and 30 respectively.

The intermediate section 12 of the stationary jaw member is provided with an opening 31 in alignment with slot 28.

The locking means for securing the adjustable jaw 22 in a locked adjusted position comprises a rotatable element generally indicated at 32 and a convex shaped member generally indicated at 34.

The rotatable element 32 has a threaded shank 33 which extends through the opening 31 and through slot 20 28 of the movable jaw member 26. The rotatable element 32 has an enlarged head 36 from which extends a lever 38 having a flattened and roughened finger gripping portion 40. The head 36 rests against the front of the intermediate section 12.

25 Engaging the opposite or free end of the threaded shank is the convex shaped member 34 which is best shown in Figures 4 and 5. The member 34 has an outside facing flat surface 42 and a convex shaped inner surface 44. Member 34 has a threaded opening 46 30 which engages the threaded shank 33. Member 34 is substantially rectangular in plan view and the opening 46 is positioned closer to one side, i.e. the right side, as viewed in Figure 5 so as to permit the adjustable jaw 22 to be moved and locked in the widest separated 35 position with respect to the stationary jaw 14.

The convex shaped surface 44 of the member 34 is extremely important and forms an essential feature of this invention. With this shape a portion of the convex surface extends inwardly into the slot 28 so that it is 40 inwardly of the outer vertical surface of the lateral extension 24 of the movable jaw and a portion of the convex surface extends outwardly beyond and rearwardly of the slot 28. That is, the upper portion of the convex surface 44 extends upwardly and outwardly or rearwardly of the slot 28 and the lower portion of the convex surface extends downwardly and outwardly or rearwardly of the slot 28. When the rotatable element 32 is tightened with respect to the convex shaped member 34, member 34 will be positioned as best shown in Figure 5 so that the convex surface 44 of member 34 engages the outer edges of the upper and lower wall surfaces 29 and 30 of slot 28. The engagement is effected along two parallel straight lines.

55 The locking arrangement just described is effective in positively locking the movable jaw 22 with respect to the stationary jaw 14. This will prevent spreading or movement of the movable jaw with respect to the stationary jaw while the same is engaging an object to 60 which it is applied when in use.

In prior art constructions using conventional nuts or locking means it has been found that when in use the movable jaw will have a tendency to move or spread with respect to the stationary jaw due to the ineffective locking of the nut or locking means, hence the same has to be repeatedly tightened during use. With the applicant's convex-shaped inner surface of member 34 and the manner in which it engages the upper and lower outer edges of the slot 28 this is positively eliminated 65 and the movable jaw is locked in an immovable position while in use.

The movable jaw member 26 may be readily adjusted

relative to the stationary jaw member. By moving the lever 38 in a slightly counterclockwise direction, as viewed in Figure 1, the convex shaped member 34 is loosened sufficiently on the shank 31 to permit the movable jaw 22 to be positioned in its desired adjusted position and then by moving the lever 38 in a slightly clockwise direction (Figure 1) the member 34 is tightened, as previously described, to positively lock the movable jaw with respect to the stationary jaw.

Figure 6 shows a modification. In this modification the intermediate recessed section 12' of the stationary jaw 14' is provided with a groove 52 extending across the intermediate section just above the lower shoulder 18'. The lateral extension 24' of the movable jaw is provided with a rib 54 which engages the groove 52 to move therewithin. This modified construction provides additional support between the movable jaw and the stationary jaw. In all other respects the construction is as previously described and it is not necessary to redescribe the same.

It will be understood that various changes and modifications may be made in the foregoing without departing from the spirit and scope of the appended claims.

We claim:

1. A slideable side jaw wrench comprising a stationary jaw member and a movable jaw member, said movable jaw member having a continuous slot at a right angle to said movable jaw member, said stationary jaw member supporting a threaded member extending into said slot, a non-rotatable locking member supported on said threaded member, said locking member having a convex shaped inner surface aligned with said slot and adapted when in locking position to engage said movable jaw member adjacent said slot and to extend partially into said slot and partially out of said slot.

2. A slideable side jaw wrench comprising a stationary jaw member and a movable jaw member, said movable jaw member having a continuous slot at a right angle to said movable jaw member, locking means for securing said movable jaw member in its adjusted position, said locking means comprising a rotatable threaded element and a non-rotatable member having a convex

shaped inner surface aligned with said slot, said threaded rotatable element being supported on said stationary jaw member and extending into said slot, said convex shaped member being secured to the free end of said rotatable threaded element and extending into said slot to engage the outer edges of the wall surfaces adjacent said slot to lock said movable jaw member against movement with respect to said stationary jaw member.

3. A slideable side jaw wrench comprising a stationary jaw member having a handle and an intermediate recessed portion, a movable jaw member having a lateral extension slideable confined in said intermediate recessed portion, said lateral extension having a continuous slot at a right angle to said stationary jaw, locking means for securing said movable jaw member in its adjusted position, said locking means comprising a rotatable threaded element and a non-rotatable member having a convex shaped inner surface aligned with said slot, said threaded element being supported on said intermediate recessed portion and extending into said slot, said convex shaped member being secured to the free end of said rotatable threaded element and extending into said slot to engage the outer edges of the wall surfaces adjacent said slot to lock said movable jaw member against movement with respect to said stationary jaw member.

4. In the structure defined in claim 3 in which said intermediate recessed portion has a groove and said movable jaw member has a rib engaging said groove.
